(57) **CLAIM**

I claim the ornamental design for a bottle, as shown and described.

DESCRIPTION

FIG. 1 is a top, front, left side perspective view of a bottle;
FIG. 2 is a left side elevational view thereof;
FIG. 3 is a right side elevational view thereof;
FIG. 4 is a rear elevational view thereof;
FIG. 5 is a front side elevational view thereof;
FIG. 6 is a top plan view thereof;
FIG. 7 is a bottom plan view thereof;
FIG. 8 is a top, front, left side perspective view of a bottle;
FIG. 9 is a left side elevational view thereof;
FIG. 10 is a right side elevational view thereof;
FIG. 11 is a rear elevational view thereof;
FIG. 12 is a front side elevational view thereof;
FIG. 13 is a top plan view thereof;
FIG. 14 is a bottom plan view thereof;
FIG. 15 is a top, front, left side perspective view of a bottle;
FIG. 16 is a left side elevational view thereof;
FIG. 17 is a right side elevational view thereof;
FIG. 18 is a rear elevational view thereof;
FIG. 19 is a front side elevational view thereof;
FIG. 20 is a top plan view thereof; and,
FIG. 21 is a bottom plan view thereof.

The broken lines are for illustrating unclaimed portions of the bottle; the broken lines form no part of the claimed design.

1 Claim, 18 Drawing Sheets
